UNITED STATES PATENT OFFICE.

CHARLES R. HOLDEN, OF ARDMORE, INDIAN TERRITORY.

DESIGN FOR A STEAM-TABLE.

SPECIFICATION forming part of Design No. 31,757, dated October 31, 1899.

Application filed September 26, 1899. Serial No. 731,774. Term of patent 7 years.

To all whom it may concern:

Be it known that I, CHARLES R. HOLDEN, a citizen of the United States, residing at Ardmore, in the county of Chickasaw, Indian Territory, have invented and produced a new and original Design for Steam-Tables; and I do declare the following to be a full, clear, and exact description of the same, reference being had to the accompanying drawing, forming a part thereof.

This invention relates to steam-tables.

The object of the invention is to provide a new design for steam-tables of the class used for keeping warm foods which have been cooked.

The principal and leading feature of my invention is the T shape of the table and appurtenances, as clearly shown in the drawing.

The design is illustrated in the accompanying drawing, in which the figure represents a perspective view of a steam-table constructed in accordance with my invention.

In the drawing, A represents a fire-chamber having in its front face a door *a* and

having at its rear end a smoke-pipe *a*². The fire-box is, as shown, arranged in the center of the structure, and resting upon it and extending at right angles therefrom is the upper main portion of the steam-table. The upper portion consists of a water-box B, having openings *b* in its upper face, and food-receptacles C, and the covers *c* of the food-receptacle. The covers are slightly tapering from their lower and their upper ends. The water-box is supported entirely by the fire-chamber and, as shown, extends an equal distance from each side thereof, the general contour of the entire steam-table and appurtenances being that of the letter T with a short stem.

Having thus described my invention, what I claim as new, and desire to secure by Letters Patent, is—

The design for a steam-table, substantially as herein shown and described.

CHARLES R. HOLDEN.
